UNITED STATES PATENT OFFICE.

HARRY VISSERING, OF CHICAGO, ILLINOIS.

BRAKE-BEAM.

SPECIFICATION forming part of Letters Patent No. 729,707, dated June 2, 1903.

Application filed January 22, 1902. Serial No. 90,794. (No model.)

To all whom it may concern:

Be it known that I, HARRY VISSERING, a citizen of the United States of America, residing at Chicago, in the county of Cook and State of Illinois, have invented certain new and useful Improvements in Brake-Beams, of which the following, taken in connection with the accompanying drawings, is a specification.

10 This invention has reference to an improvement in brake-beams made, preferably, of metal, and is designed particularly with the object of reducing the cost of construction of such beams and improving the strength and durability thereof, particularly the strength in a vertical direction—that is, as against strain exerted above or below the beam, tending to bend it upward or downward.

15 A further object of this invention is the provision of a brake-beam composed of two members arranged one above and the other below a casting in the middle of the beam, which forms a fulcrum-post for the brake-beam lever, said two members being brought 20 together at their ends and united by means of suitable end castings or brake-shoe heads, which may be of any preferred type.

25 A further object of my invention is the provision of a brake-beam composed of two channel members placed back to back on a horizontal plane or plane which is longitudinal of the main strain to which the beam is subjected and spaced apart between their ends by means of a suitable casting, forming a 30 part of the fulcrum-post device which takes the brake-beam lever.

35 The above, as well as such other objects as may hereinafter appear, I attain by means of a construction which I have illustrated in the 40 accompanying drawings, in which—

45 Figures 1 to 6, inclusive, show the preferred form with its details, and Figs. 7 to 10, inclusive, various modifications thereof. Fig. 1 is a plan view of my improved brake-beam. Fig. 2 is a front elevation thereof—that is, an elevation looking at the beam from the side which is toward the axle when the beam is in use. Fig. 3 is a section taken on the line 3 of Figs. 4 and 5. Fig. 4 is a sectional view 50 taken on the line 4 of Fig. 2. Fig. 5 is a sectional view taken on the line 5 of Fig. 2. Fig. 6 is a sectional view taken on the line 6 of

Fig. 1, showing the improved form of hanging device which I employ. Fig. 7 shows a modification of my beam in which a different 55 form of fulcrum-post is used. Fig. 8 is a front elevation of the beam shown in Fig. 7. Fig. 9 is a detail of the fulcrum-post shown in Figs. 7 and 8, and Fig. 10 another view of the same fulcrum-post.

60 Referring now more particularly to Figs. 1 to 6, inclusive, it will be seen that in the construction of my improved beam I provide first a pair of channels or other commercially-rolled shapes equivalent thereto, which I have marked 11, the said channels being secured together at their ends by means of end castings 12, which I prefer to construct as brake-shoe heads to avoid the necessity for using additional heads besides the castings 65 required for holding the two channels together. Between the two ends of the beam the channels 11 are spaced apart by means of the fulcrum-post, so as to stiffen the beam vertically and prevent the bending thereof in 70 this direction, which is common in beams of this class, which are otherwise amply strong—that is, which are sufficiently strong so far as taking the strains of braking is concerned. The channels, as shown, are arranged back 75 to back—that is, with their web portions in contact at the ends—since this I believe to be 80 more suitable for the purpose.

85 Adjacent to the ends of the beam I provide a combined guard-finger device and hanger, comprising, essentially, a guard-finger piece 13, which has a wedge-shaped extension 14, projecting between the two channels in position to have the bolt 15 pass through it and secure it in place, the bolt 15 being also made 90 to form a safety chain-hook, comprising, essentially, an eye 16, provided with a flattened part 17, (see Fig. 6,) that bears against the channel 11 in a manner to prevent rotation of said bolt when the nut 18 is put on or 95 taken off.

100 The preferred form of fulcrum-post is that which I have shown in Figs. 1, 4, and 5, and comprises, primarily, the socket-piece 19, which is riveted or otherwise secured between the two channel members 11 and carries the pull or clevis rod 20, which is provided at 21 with trunnions arranged with a curved bearing-surface 22, so that the clevis-

rod 20 will have a movement vertically to accomodate itself to the direction of pull upon the brake-beam lever, this vertical movement being permitted by the clearance-space 23 5 above and below the clevis-rod and within the socket-piece 19. At the back of the beam the socket-piece is provided with projections 24, constructed to engage the rear flanges of the channels, the projections 24 being preferably lipped over, as shown at 25, on their ends in order to help retain the channels and other parts in proper relative position.

In Figs. 7 to 10 I have shown a modified arrangement of my improved mechanism in 15 which I employ a fulcrum-post 26 which is made all in one piece in place of the improved form which I have shown in the other figures. Otherwise the construction shown in these Figs. 7 to 10 is substantially like that shown 20 in the other views and has corresponding parts numbered with the same reference-numbers.

Having thus described my invention, what I claim as new, and desire to secure by Letters 25 Patent, is—

1. A brake-beam comprising two channel-bars with their flanges directed outwardly, and spaced apart and held at their middle by a pull-rod block, and having their ends secured by insertion in a brake-head, substantially as described.

2. The combination with a brake-beam composed of two channel-bars separated along a horizontal plane, of a guard-finger secured 35 between said two members and held by a hooked bolt, substantially as described.

3. The combination with a brake-beam composed of two members separated on a horizontal plane, of a safety chain-bolt passing 40 through said members, and having a flattened portion thereon adapted to engage with one

of said members, whereby to prevent rotation of the bolt, substantially as described.

4. A brake-beam composed of two channel-bars spaced apart at the middle on a horizontal plane, combined with a guide-rod between said bars, a fastening therefor composed of a suspension-bolt through the bars and rod, having an open hook bearing on the beam, whereby a chain in said hook may be detached 50 without removing said suspension-bolt.

5. The combination with a brake-beam composed of two members separated on a horizontal plane, of a fulcrum-post constructed to be introduced between the two ends of said members and spacing the same apart, said fulcrum-post comprising a body portion, and a clevis-rod movable relatively to said body portion, and in a direction vertical relative 55 to the beam when it is in use.

6. A brake-beam fulcrum-post comprising a body portion, and a pull-rod secured to said body portion provided with a T-head allowing movement in one plane only relative thereto.

7. A brake-beam fulcrum-post comprising a body portion, and a clevis-rod, having trunnions engaging said body portion, substantially as described.

8. A brake-beam fulcrum-post comprising 70 a body portion, and a device for carrying the brake-beam strains to said body portion, having trunnions engaging said body portion, substantially as described.

In testimony whereof I have hereunto set 75 my hand in the presence of two subscribing witnesses.

HARRY VISSERING.
